US00D357163S

United States Patent [19]

Izumisawa

[11] Patent Number: Des. 357,163

[45] Date of Patent: ** Apr. 11, 1995

[54] DUST FREE DUAL ACTION SANDER

[75] Inventor: Nobuyuki Izumisawa, Tokyo, Japan

[73] Assignee: Shinano, Inc., Saitama, Japan

[**] Term: 14 Years

[21] Appl. No.: 9,289

[22] Filed: Jun. 9, 1993

[52] U.S. Cl. D8/62

[58] Field of Search ..... D8/61, 62; 51/170, 170 R,
51/170 TL, 170 T, 170 MT
